UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

COMMINUTING MILL.

Application filed April 7, 1921. Serial No. 459,332.

To all whom it may concern:

Be it known that RAY C. NEWHOUSE, a citizen of the United States, residing at Wauwatosa, in the county of Milwaukee and 5 State of Wisconsin, has invented a certain new and useful Improvement in Comminuting Mills, of which the following is a specification.

This invention relates in general to improvements in the art of reducing materials such as mineral, hard animal or vegetable substances, by impact and abrasion, and relates more specifically to improvements in the construction and operation of rotary 15 drum mills for comminuting materials with the aid of a plurality of tumbling bodies such as balls, pebbles, rods and the like.

An object of the invention is to provide a comminuting mill which is simple in construction and efficient in operation.

It has been found in the operation of tube mills, ball mills, rod mills and the like, that considerable available energy is ordinarily wasted due to the cushioning of the tumbling 25 comminuting bodies, by the material which is in pulverulent condition. This fine material lodges upon the comminuting bodies and packs about the larger particles of material which require further reduction, thereby preventing the cascading and tumbling comminuting bodies from effectively pulverizing 30 the larger particles of the charge.

In order to make available this energy which is ordinarily wasted due to the cushioning effect produced by the fine particles of material, the present invention contemplates removal of the fine material from the charge, at one or more points along the mill. The invention also contemplates return for 40 further reduction, of the relatively large particles of material which are discharged from the mill during the process of elimination of the fines.

A further object of the present invention 45 is to provide a mill which will deliver exceedingly uniform and fine material at the final discharge. Another object of the invention is to provide a simple and compact comminuting mill in which the parts which 50 are subjected to excessive wear, are readily

accessible for inspection and renewal. An additional object of the invention is to provide a compound or multi-stage comminuting mill having screening means of ample capacity between the successive grinding 55 stages of the mill. The invention further contemplates the provision of other improvements in construction and operation of mills of the general character referred to, whereby the cost of manufacture is reduced to a 60 minimum and the efficiency of operation is increased to a maximum.

A clear conception of several embodiments of the invention and of the operation of devices constructed in accordance therewith, 65 may be had by referring to the drawings accompanying and forming a part of this specification, in which like reference characters designate the same or similar parts in the various views.

Fig. 1 is a somewhat diagrammatic central vertical section through a rotary combination comminuting mill embodying means for separating the material which has been sufficiently reduced in the first grinding stage, from the oversize; the mill being provided with means for delivering the separated material to the second stage for final reduction and with other means for returning the oversize material to the first stage 75 for further reduction.

Fig. 2 is an enlarged transverse vertical section through the combination comminuting mill, part of the section being taken through the mill division head, and another 85 part being taken in front of the division head with reference to the direction of flow of the material through the mill.

Fig. 3 is an enlarged transverse vertical section through the combination comminuting mill, the section being taken through the instrumentalities for returning material which requires further reduction, to the second stage of the mill.

Fig. 4 is a purely diagrammatic illustration of a rotary combination comminuting mill provided with means for introducing material to the mill at a point intermediate its ends.

Figs. 5 to 11 inclusive are purely dia-

100

grammatic illustrations disclosing various combinations with respect to the flow of materials, which may be utilized to advantage with mills constructed in accordance with the present invention.

The rotary combination or two-stage comminuting mill disclosed in detail in Figs. 1 to 3 inclusive, comprises in general a rotary drum or shell 1 which may have uniform diameter throughout its length, the shell 1 being provided with feed and discharge end heads 2, 3 respectively, and having therein a partition or division head 4 which divides the shell 1 into successive coarse and fine grinding chambers 5, 6 respectively, these chambers constituting the stages of the mill. The mill is rotatably mounted in suitable trunnion bearings 7, 8 located in proximity to the end heads 2, 3 respectively, and is adapted to be continuously rotated about its horizontal center line at a desirable speed by means of power applied to a driving gear 9 associated with one end of the mill.

The preliminary or coarse grinding chamber 5 is ordinarily filled to near the horizontal center line of the shell 1 with relatively large freely tumbling comminuting bodies 10 disclosed as balls, while the fine grinding or finishing chamber 6 is likewise filled to near the horizontal center line of the shell 1 with relatively small freely tumbling comminuting bodies 11 likewise disclosed as balls. The comminuting bodies 10, 11 are free to tumble and cascade within the chambers 5, 6, and are preferably formed of material which will effectively resist impact and abrasion. The bodies 10, 11 may assume a variety of forms and may in some cases be shaped as rods extending substantially the entire length of the chamber within which they are located. The raw material is fed into the coarse grinding chamber 5 through an inlet trunnion 70. Within the chamber 5 the material is partially reduced by the action of the large comminuting bodies 10, the partially reduced material which is of sufficient fineness to pass through the holdback plate 19 and screen 14, being delivered to a receptacle 17 located below and entirely outside of the mill. From the receptacle 17 below the mill, the material which has been discharged from the first grinding stage through the screen 14, is delivered to the fine grinding or finishing chamber 6 by means of a pair of return scoops 16 formed as shown in Fig. 3. The material thus delivered to the fine grinding or second stage, is further reduced in the chamber 6 by the action of the tumbling comminuting bodies 11. The finally reduced material is eventually delivered from the finishing chamber 6 through a discharge screen 26 and into the path of elevating vanes 12 which auto-

matically discharge the fine material from the mill through the discharge trunnion 80.

The mill partition or division head 4 comprises a combined holdback and screening plate 19 preferably formed in sections, an imperforate wall disposed parallel to the plate 19, a plurality of radial ribs 23 which divide the space between the plate and wall into a series of chambers 22 communicating directly with the coarse grinding chamber 5 through perforations in the plate 19, an annular sizing screen 14 completely surrounding the mill and spaced therefrom to form an annular screening chamber located outside of the shell but communicating with the chambers 22 through radial openings 20 in the shell 1, diametrically opposite rejects return vanes 13 having adjacent conducting passages which are segregated from the chambers 22, scoop plates 21 connecting the return vanes 13 with the screen 14, and return openings 25 extending from the vanes 13 through a central projecting portion 18 which extends away from the partition 4 and inwardly toward the feed end of the mill. The material delivered from the coarse grinding chamber through the perforations in the holdback plate 19, drops by gravity through the openings 20 and upon the annular sizing screen 14. As this material slides along the inner surface of the screen 14 during rotation of the mill, the relatively fine material passes through the screen perforations and drops into the receptacle 17 below. The scoop plates 21 during each half revolution of the mill catch the oversize particles of material which have passed through the perforations in the holdback plate 19 but which are too large to pass through the screen 14, and deliver these oversize particles to the vanes 13 which periodically shoot the collected batches of oversize material back into the medial portion of the coarse grinding chamber 5 through the return openings 25, for further reduction by the comminuting bodies 10. The inwardly extending portion 18 of the division head 4 besides serving to provide passages for conducting the oversize into a medial portion of the chamber 5 and remote from the plate 19, serve to throw the relatively large comminuting bodies 10 into the medial portion of the coarse grinding chamber and away from the plate 19 and the openings 25. By thus preventing the large tumbling comminuting bodies 10 from lodging in front of the plate 19, the material is permitted to pass through this plate with least obstruction thereby enhancing the capacity of the mill. A further advantage in constructing the inwardly extending portion 18 in the manner shown is that, as the comminuting bodies 10 are thrown into the medial portion of the coarse grinding chamber 5, the larger of the bodies

tend to roll further than the smaller, so that there is a classification of the comminuting bodies 10, resulting in grading the size of the comminuting bodies in proportion with the size of the material being reduced. The shooting of the oversize material into the medial portion of the grinding chamber 5 causes it to be further acted upon by the comminuting bodies 10 before it can again pass through the plates 19.

The material delivered to the receptacle 17 may in some cases be derived from other sources than the coarse grinding chamber 5, and may also in some instances be classified in order to remove therefrom that portion which requires no further reduction. In the form of mill disclosed in Figs. 1, 2 and 3, all of the material which is delivered from the screen 14 is eventually returned to the mill by means of the revolving scoops 16. These scoops 16 during rotation of the mill, intermittently pick up batches of material from within the receptacle 17 and deliver this material into the end of the finishing chamber 6 remote from the discharge end of the mill, through nozzles or injectors 15 which have delivery passages so movable and directed that the material from within the finishing chamber 6 will not return to the scoops 16. The portion of the mill in proximity to the division head 4 and the scoops 16 may be provided with a suitable removable housing or guard 24 as shown. This guard is made readily removable in order to permit access to the screen 14 and the scoops 16. The operation of the mill disclosed in Figs. 1, 2 and 3 should be readily apparent from the foregoing description.

It will be noted that the return scoops 16 may also be employed to inject other materials than that delivered from a preceding stage of the mill, to the interior of the mill at any point intermediate its ends. In the diagram designated as Fig. 4, the scoops 16 are adapted to inject material to a mill of the two-stage or combination type from a trough 77, at a point intermediate the ends of the finishing chamber 6. In this particular mill the division head 40 comprises a combined holdback and sizing screen 19 through which the material discharged from the coarse grinding chamber 5 is delivered into the path of revolving elevating vanes 33 which convey material thus elevated into the inlet end of the second stage or finishing chamber 6 through central discharge openings 35. When the material thus admitted to the finishing chamber 6 has been further reduced to a sufficient extent, it may be desirable to admit other material to the mill from an outside source such as the trough 77 for the purpose of thoroughly mixing it with the comminuted material, and possibly also in order to pulverize said added material. The scoops 16 provide

simple and efficient means for thus admitting additional material to the mill. Material thus added is intimately mixed with the charge within the mill during its travel from the scoops 16 to the discharge trunnion 80. It will be understood of course that the mill disclosed in Fig. 4 should be provided with the usual discharge mechanism and with other details of construction necessary to complete the structure. The scoops 16 may be located at any desired point or points along the mill and may be utilized to introduce various materials into the mill.

Referring specifically to the material flow diagrams illustrated in Figs. 5 to 11 inclusive, it will be noted that in each of these figures the material delivered from the first sizing screen 14 is discharged directly to a classifier 117 as indicated by the flow line 31. In the device illustrated in Fig. 5, the fine material which is separated from the oversize in the classifier 117 is finally discharged as indicated by the flow line 30. The oversize material is delivered into the finishing chamber 6 by means of the scoops 16 as indicated by the flow line 32. From the finishing chamber 6 the finally reduced material is delivered through the discharge trunnion 80, this finally reduced material in some cases requiring no further classification or reduction.

In the diagram designated as Fig. 6, the material passing through the screen 14 as indicated by the flow line 31 is mixed with the material delivered from the fine grinding chamber 6 through the discharge trunnion 80 as indicated by the return flow line 34. The mixture of materials is delivered to the classifier 117 wherein the sufficiently comminuted material is separated from the oversize and the finished product is discharged as indicated by the flow line 30. The oversize material from the classifier 117 is returned to the mill and is delivered into the fine grinding chamber 6 for further reduction. With this arrangement the product finally delivered as indicated by the flow line 30 will be exceedingly uniform since the classifier 117 will also remove particles passing through the trunnion 80, which require further reduction.

In the diagram designated as Fig. 7 the material delivered from the sizing screen 14 as indicated by the flow line 31, passes directly to the classifier 117 which separates the oversize from the material which has been sufficiently reduced, finally discharging the latter as indicated by the flow line 30. The oversize from the classifier 117 is returned to the mill and delivered into the finishing chamber 6 by means of the scoops 16 as indicated by the flow line 32. After having been further reduced in the finishing chamber 6, the material is delivered from the mill through the discharge trunnion 80

and is mixed with the fine material delivered from the classifier 117 as indicated by the flow line 34.

When reducing materials having certain characteristics or when exceedingly fine and uniform final product is desired, it may be found advantageous to apply the present invention to mills having more than two grinding stages, as shown in Figs. 8 to 11 inclusive. In each of these diagrams, the mill is divided into three successive comminuting chambers 5, 39, 6 having comminuting bodies of graded sizes therein. While these figures disclose mills having three successive chambers, it will be obvious that more chambers may be provided if desired, by merely inserting more division heads 4.

In the diagram designated as Fig. 8, the material delivered from the coarse grinding chamber 5 past the first sizing screen 14 as indicated by the flow line 31, passes directly to the first classifier 117. In the first classifier 117, the fine particles some of which may require further reduction, are separated from the larger particles, and are sent to the second classifier as indicated by the flow line 30. The larger particles delivered from the first classifier 117 are returned to the mill and are introduced into the intermediate grinding chamber 39 by means of the first set of scoops 16 as indicated by the return flow line 32. After having been further reduced in the intermediate stage, the oversize from the first classifier 117 is delivered past the second sizing screen 14 to the second classifier 117 as indicated by the flow line 36. The finished product is delivered from the second classifier 117 as indicated by the flow line 38, while the oversize from this classifier is sent back to the mill being introduced into the finishing chamber 6 by means of the second set of scoops 16 as indicated by the second return flow line 37. After having been finally reduced in the finishing chamber 6, the remaining material is delivered from the mill through the discharge trunnion 80.

In the diagram designated as Fig. 9, the material delivered from the coarse grinding chamber 6 past the first sizing screen 14 as indicated by the flow line 31, passes directly to the single classifier 117. The fine material discharged from the classifier 117 is sent directly to the finishing chamber 6 as indicated by the flow line 30, while the oversize from the classifier is sent to the intermediate chamber 39 as indicated by the flow line 32, for further reduction. The material delivered from the intermediate stage past the second sizing screen 14 as indicated by the flow line 36, is mixed with the fine product delivered from the classifier 117, and is likewise returned to the mill and delivered into the finishing chamber 6, for final

reduction. The finished product is delivered from the chamber 6 through the discharge trunnion 80.

In the diagram designated as Fig. 10, the material delivered from the coarse grinding chamber 5 past the first sizing screen 14 as indicated by the flow line 31, passes directly to the first classifier 117. In the first classifier 117, the finished product is separated from the larger particles, and is discharged as indicated by the flow line 30. The larger particles delivered from the first classifier 117 are returned to the mill and are introduced into the intermediate grinding chamber 39 for further reduction, by means of the first set of scoops 16 as indicated by the return flow line 32. After having been further reduced in the intermediate stage, the oversize from the first classifier 117 is delivered past the second sizing screen 14 to the second classifier 117 as indicated by the flow line 36. The finished product delivered from the second classifier as indicated by the flow line 38, is mixed with the finished product from the first classifier as indicated, while the oversize from the second classifier 117 is returned to the mill and is introduced into the finishing chamber 6 for final reduction, by means of the second set of scoops 16 as indicated by the return flow line 37. After being finally comminuted in the finishing chamber 6, the remaining material is delivered from the mill through the discharge trunnion 80 as indicated by the flow line 34, and is mixed with the finished product delivered from the two classifiers 117, as indicated.

In the diagram designated as Fig. 11, the material delivered from the coarse grinding chamber 5 past the first sizing screen 14 as indicated by the flow line 31, passes directly to the first classifier 117. In the first classifier 117, the relatively fine material is separated from the larger particles, and is sent to the second classifier 117 as indicated by the flow line 30. The larger particles delivered from the first classifier 117 are returned to the mill and are introduced into the intermediate grinding chamber 39 for further reduction by means of the first set of scoops 16 as indicated by the return flow line 32. After having been further reduced in the intermediate stage 39, the oversize from the first classifier is delivered past the second sizing screen 14 to the second classifier 117 as indicated by the flow line 36. The large particles discharged from the second classifier 117 are returned to the mill and are introduced into the finishing chamber 6 for final reduction, by means of the second set of scoops 16 as indicated by the return flow line 37. After having been further reduced in the finishing chamber 6, the remaining material is delivered from the mill through the discharge

trunnion 80 as indicated by the flow line 34, and is also sent to the second classifier 117. In the second classifier the finished product is separated from the material introduced thereto from the three sources indicated by the flow lines 30, 34, 36, and is delivered as indicated by the flow line 38.

It will be noted that by employing the systems which have been graphically illustrated in Figs. 5 to 11 inclusive, as well as others of a similar nature, materials having various characteristics may be reduced to produce final products having various degrees of fineness. It will also be obvious that materials from sources outside of the mill may be introduced to one or more of the mill chambers 5, 39, 6. The shell 1 may also be formed of several diameters and may be gradually tapered for all or a portion of its length.

From the foregoing description, it will be obvious that the efficiency of a mill constructed in accordance with the present invention, is increased to a maximum by removing the sufficiently reduced product at one or more points along the mill. The provision of sufficient screening area at the discharge ends of the several chambers, permits rapid delivery of the materials from the chambers thereby producing a mill of large capacity. The screens 14 and scoops 16 are readily accessible being located outside of the shell 1. The mill is capable of operation either as a wet or dry mill without departure from the invention, and is of exceedingly simple and compact internal construction.

It should be understood that it is not desired to limit the invention to the exact details of construction and of operation herein shown and described for various modifications within the scope of the claims may occur to persons skilled in the art.

It is claimed and desired to secure by Letters Patent:

1. In a comminuting mill, a rotary drum, means for introducing material into an end of said drum, and an external scoop movable with said drum to introduce material from an outside source directly into said drum remote from said end, a portion of said scoop extending transversely of the drum axis and substantially parallel to the drum periphery.

2. In a comminuting mill, a rotary drum, means for introducing material into an end of said drum, and an external scoop movable with said drum to introduce material from an outside source directly into said drum remote from said end, said scoop extending approximately half way around and substantially parallel to the drum periphery.

3. In a comminuting mill, a rotary drum, means for introducing material into an end of said drum, a classifier independent of the

mill, and an external scoop movable with said drum to introduce material from said classifier directly into said drum remote from said end, a portion of said scoop extending transversely of the drum axis and substantially parallel to the drum periphery.

4. In a comminuting mill, means dividing the mill into successive chambers, and means for automatically introducing material directly into the periphery of one of said chambers from an outside source at a point intermediate the ends of said chamber.

5. In a comminuting mill, means dividing the mill into successive chambers, means for delivering material entirely free from a chamber at one side of said dividing means, and means for introducing said material directly into the periphery of another chamber from an outside source on the other side of said dividing means.

6. In a comminuting mill, means dividing the mill into successive chambers, a classifier independent of the mill, means for delivering material from the mill to said classifier at one side of said dividing means, and means for introducing material from said classifier to the mill at the opposite side of said dividing means.

7. In combination, a comminuting mill, means dividing the mill into successive chambers, means for delivering material from one of said chambers, and means for returning part of said material into the periphery of another of said chambers from a source independent of said mill at a point intermediate the ends of said latter chamber.

8. In a combination comminuting mill, means dividing the mill into successive chambers, means for grading the material delivered from one of said chambers, said grading means being adapted to deliver the finer material free from the mill and to return the oversize to said chamber, and an external scoop for returning said finer material into the periphery of another chamber of said mill from a source independent of said mill.

9. In a comminuting mill, a shell forming a chamber, a plurality of comminuting bodies in said chamber, a screen in communication with said chamber, and a central conveying projection having a tapered outer bounding surface and extending into said chamber for automatically classifying the comminuting bodies adjacent to said screen during operation of the mill.

10. In a comminuting mill, a shell and a division head forming a chamber, a screen in said division head and in communication with said chamber, a plurality of comminuting bodies within said chamber, and a central conveying projection having a peripherally smooth tapered outer bounding surface and extending into said chamber for automatically classifying the comminuting

bodies adjacent to said screen during operation of the mill.

11. In a comminuting mill, a shell forming a plurality of chambers, a division head between successive chambers of said shell, a screen in said division head for grading material delivered from one of said chambers, a second screen located outside of the mill for grading material passing said first screen, means for returning the rejects from said second screen to a medial portion of said chamber, and means for introducing the material passing said second screen into a subsequent chamber of the mill.

12. In combination, a rotary drum having uniform diameter throughout its length, a partition dividing said drum into a plurality of chambers, comminuting means in each of said chambers, means connected with said partition for delivering reduced material from one of said chambers, a stationary receptacle adapted to receive said reduced material, and means connected with said drum for feeding material from said receptacle into another of said chambers.

13. In combination, a rotary mill comprising a drum having uniform diameter throughout its length and having comminuting means therein, means for removing material from a medial portion of said mill, a receptacle independent of said mill adapted to receive reduced material, and means operable by said rotating mill for returning material from said receptacle into a medial portion of said drum.

14. In combination, a rotary mill having comminuting means therein, means for removing material from a medial portion of said mill, a receptacle independent of said mill adapted to receive reduced material, and an external peripheral scoop movable with said rotating mill for returning material from said receptacle into a medial portion of said mill.

15. In combination, a rotary mill having a partition forming a plurality of chambers, comminuting means in each of said chambers, means connected with said partition for delivering reduced material from one of said chambers, a stationary receptacle adapted to receive said reduced material, and means connected with said mill laterally of said partition for feeding material from said receptacle into another of said chambers.

16. In combination, a rotary mill having comminuting means therein, means for removing material from a medial portion of said mill, a receptacle independent of said mill adapted to receive reduced material, and means operable by said rotating mill for returning material from said receptacle into a medial portion of said mill located laterally of said material removing means.

17. In combination, a rotary mill having

a plurality of comminuting chambers therein, means connected with said mill for discharging reduced material from one of said chambers, a receptacle separate from said mill for receiving said reduced material, and means connected with said mill for feeding material from said receptacle directly into another of said chambers.

18. In a comminuting mill, a shell forming a chamber, comminuting bodies in said chamber, a screen in communication with said chamber, and a central peripherally smooth conveying projection extending into said chamber coaxially with said mill for automatically classifying the comminuting bodies adjacent to said screen during operation of the mill.

19. In combination, a rotary mill having a partition forming a plurality of chambers, comminuting means in each of said chambers, means connected with said partition for delivering reduced material from one of said chambers, a stationary receptacle adapted to receive said reduced material, and a scoop connected with said mill but independent of said partition for feeding material from said receptacle into another of said chambers.

20. In a comminuting mill, a rotary drum, means for introducing material into an end of said drum, and a pair of oppositely disposed external scoops movable with said drum to introduce material from an outside source directly into diametrically opposite portions of said drum remote from said end, a portion of each of said scoops extending transversely of the drum axis and substantially parallel to the drum periphery.

21. In a comminuting mill, a rotary drum having uniform diameter throughout its length, means for introducing material into an end of said drum, and an external scoop movable with said drum to introduce material from an outside source directly into said drum remote from said end, a portion of said scoop extending transversely of the drum axis and substantially parallel to the drum periphery.

22. In a comminuting mill, means dividing the mill into successive chambers, a classifier independent of the mill, means for delivering material from the mill to said classifier at one side of said dividing means, and an external scoop for introducing material from said classifier to the mill at the opposite side of said dividing means.

23. In a comminuting mill, a rotary drum, means dividing said drum into successive chambers, a classifier independent of said drum but located in proximity thereto, means for discharging material from one of said chambers to said classifier, and a scoop movable with said drum for introducing material from said classifier to another of said chambers.

24. In a comminuting mill, a rotary drum, a partition dividing said drum into successive chambers, a classifier independent of said mill located adjacent to the periphery of said drum, means for delivering reduced material from an initial chamber of said drum to said classifier, and an external scoop

movable with said drum for returning a portion of said material from said classifier to a subsequent chamber of the mill.

In testimony whereof, the signature of the inventor is affixed hereto.

RAY C. NEWHOUSE.
